SPRAYING UNIT

Filed Feb. 16 1928

INVENTOR:
Adam A Breuer

By: Charles H. Hays

UNITED STATES PATENT OFFICE

ADAM A. BREUER, OF CHICAGO, ILLINOIS

SPRAYING UNIT

Application filed February 16, 1928. Serial No. 254,717.

This invention relates to spraying devices of the type in which the liquid is projected in the form of a spray suspended in a current of air.

5 Usually sprays of this type are hand operated and consequently are intermittent in action and low in throwing power.

Further it has been customary to use metal liquid containers so that the amount of liquid therein at any time cannot be seen.

One of the principal objects of the present invention is to provide a simple, readily operated and cheap form of power driven spraying device.

15 A further object of the invention is to provide a simple form of spraying device adapted to the use of a glass liquid container.

Other and further important objects of 20 this invention will be apparent from the disclosures in the accompanying drawings and the following specification.

The invention (in a preferred form) is illustrated on the drawings and hereinafter 25 more fully described.

On the drawings:

Figure 1 is a side elevation of a spray constructed in accordance with my invention.

30 Figure 2 is a central vertical section through the discharge end of the sprayer on the line II—II of Figure 3.

Figure 3 is a section on the line III—III of Figure 2.

35 As shown on the drawings:

The spraying device includes an electrically driven fan 1 of the type commonly employed in vacuum cleaners having inlet and outlet orifices 2 and 3, respectively. A 40 handle 4 is attached to the motor casing and provided with a snap switch 17 for controlling the operation of the device.

The under side of the air discharge pipe 45 5 of the spray is formed with a flat seat so that the cap of a glass Mason jar 7 may be clamped thereagainst. In this flat seat a slot is cut centrally and longitudinally and a similar registering slot is cut in the cap 50 6 and also in a felt or other washer 8 adapt-

ed to fit inside the cap and covered with tin or lead foil 9.

The cap and washer are clamped against the seat on the under side of the discharge pipe by a disc 10 held in place by screws 55 11. On the upper side of this disc is a projecting portion 12 of substantially the same size as the slot and formed so that its upper surface is substantially flush with and a continuation of the inner wall of the 60 pipe 5 except for a small lug 13. In the rear of the lug 13 is an air passage 14 passing through the disc 10 and its projection 12. The lug being disposed immediately in front 65 of this passage acts as a deflector in aiding flow of air into the jar 7 through this passage.

The cap 6 has a threaded margin adapted to engage the threaded top of the glass jar 7. Extending from the rear bottom corner 70 of the jar is a liquid supply tube 15 which passes through an aperture in the disc 12 and its projection 13. Conveniently the tube 15 is soldered or brazed to the disc 12. At its outer or discharge end the tube 75 15 is provided with a nozzle 16.

It will be noted that the bottom of the jar 7 and the bottom of the handle 4 are in the same plane so that the spraying device will stand firmly on any flat surface.

I am aware that many changes may be made and numerous details of construction may be varied through a wide range without departing from the principles of this invention, and I therefore do not propose limiting the patent granted hereon otherwise than necessitated by the prior art.

I claim as my invention:

1. A spraying apparatus including a blower, an air discharge pipe leading from said blower, an open mouthed receptacle for a liquid, a cap removably secured to the underside of said discharge pipe, said receptacle and said cap having interfitting elements for securing the same together, a jet for liquid disposed to discharge liquid into the stream of air passing through said discharge pipe in the same direction as the flow of air in said pipe, a pipe extending from said jet to a point within the receptacle 90 95 100

adjacent the bottom thereof, a disc cooperating with said discharge pipe for securing said cap in position on said pipe, said disc having a permanently open air passage therethrough leading from the discharge pipe into the receptacle to allow air pressure in the discharge pipe to act on the liquid in the receptacle and force it up the second mentioned pipe and out through said jet.

2. A device of the kind set forth comprising a blower, an air discharge pipe leading therefrom having a slot in the underside, an open-mouthed receptacle having a threaded lip, a correspondingly threaded cap, said cap having a slot adapted to register with the slot in said discharge pipe, a closure member for said slots having portions extending lengthwise of said slots over the adjacent portions of the cap, means for releasably clamping said closure member to the said discharge pipe and thereby holding said cap in position, a pipe for liquid passing through and supported by said closure member, said member being also provided with an air passage to allow the air pressure in the discharge pipe to act on the liquid in the jar and force it up the second pipe and out through said pipe.

3. A device as in claim 2 in which the upper surface of the closure member is substantially flush with the inner wall of the discharge pipe except for a projecting lip adjacent the air passage in said member adapted to aid in deflecting a portion of the air passing through said discharge pipe through said passage.

4. A spraying apparatus including a blower, an air discharge pipe leading therefrom and having an aperture in the underside of the pipe, an open mouthed receptacle, a cap, said receptacle and cap having interfitting connections for securing the same together, said cap having an aperture adapted to register with the aperture in said discharge pipe, a disc having a portion entering said apertures and having a portion engaging the inside surface of said cap for attaching said cap to said discharge pipe with the apertures in registering position, and a pipe for liquid passing through said disc and terminating within the receptacle at a point adjacent the bottom of the same.

5. A sprayer unit including in combination, a blower, a discharge pipe therefor, said pipe having a seat on its under side, said seat having an opening therethrough communicating with the interior of said pipe, a block removably associated with said seat and having a projecting part extending into said aperture, a container cap clamped between said seat and said block, said block having an air passage through it from top to bottom, a liquid discharge pipe

supported in said block, said liquid discharge pipe having its discharge end within said air pipe and adjacent the discharge end thereof, said liquid discharge pipe extending downwardly in an inclined direction below said block, and a container removably associated with said clamped container cap, the lower end of said liquid discharge pipe terminating adjacent a lower rear portion of said container.

6. A sprayer unit including in combination, a blower, a discharge pipe therefor, said pipe having a seat on its under side, said seat having an opening therethrough communicating with the interior of said pipe, a block removably associated with said seat and having a projecting part extending into said aperture, the upper surface of said projecting part being flush with the bottom of said discharge pipe, a container cap clamped between said seat and said block, said block having an air passage through it from top to bottom, said block having a deflector adjacent the upper end of said passage and behind the same with respect to the direction of air movement through said discharge pipe, a liquid discharge pipe supported in said block, said pipe having its discharge end within said air discharge pipe and adjacent the discharge end thereof, said liquid discharge pipe extending downwardly below said block, and a container removably associated with said clamped container cap.

In testimony whereof I have hereunto subscribed my name at Chicago, Cook County, Illinois.
